UNITED STATES PATENT OFFICE.

JOSEPH SACHS, OF HARTFORD, CONNECTICUT.

SWITCH.

1,257,534.

Specification of Letters Patent. Patented Feb. 26, 1918.

Application filed April 17, 1915. Serial No. 22,074.

To all whom it may concern:

Be it known that I, JOSEPH SACHS, a citizen of the United States, residing at Hartford, in the county of Hartford and State of Connecticut, have invented certain new and useful Improvements in Switches, of which the following is a specification.

This invention relates to switches, and while the invention is susceptible of general use in the art indicated, it is of particular utility when incorporated in a pendant snap switch such as shown in the drawings accompanying and forming part of the present specification, wherein I represent in detail that one of the several forms of embodiment of the invention which I have selected for illustration in said drawings. Among the objects of the invention are the provision of an article of the character set forth, which is simple in construction, quite compact, the parts of which can be inexpensively made and readily assembled and which when correlated are positive and certain in action.

Referring to said drawings:

25 Figure 1 is a side elevation of a switch involving my invention.

Fig. 2 is a longitudinal vertical sectional view of said switch.

Fig. 3 is a top plan view of the same with the upper section of the casing removed.

Fig. 4 is a longitudinal central section, the section being at right angles to that of Fig. 2.

Fig. 5 is a top plan view of the supporting body.

35 Fig. 6 is a perspective view of the switching member and its support, actuating means and certain co-operative elements, including the snap movement.

Fig. 7 is a detail view of a gear and co-40 operative actuating members.

Like characters refer to like parts throughout the several views.

The different parts of the switch are sustained by a suitable body such as that detailed by 2 and which is of some suitable insulating material as porcelain. In practice this body is surrounded by a suitable casing as 3 generally made of sheet metal and which as shown comprises lower and upper sections connected in some convenient manner as by a screw-thread joint. The casing 3 is connected with the insulating body 2 in some convenient manner. As shown the lower or main section of said casing has a perforation in its bottom to receive the screw 4, which extends through a

hole 5 in the bottom of the insulating body 2. Said hole 5 opens into the depression 6 shown as square, and which receives the nut 7 of suitable insulating material, the nut being of a shape corresponding to that of the depression 6, so that the nut is held against turning in the depression 6 when the threaded portion of the screw 4 is screwed into said nut. This depression 6 extends approximately centrally from the cavity or chamber 8 of the body 2. The inner end or top of the screw 4, it will be noted, is below or extends short of the bottom of the chamber 8. In this cavity or chamber 8 is fitted the base portion of a metallic support hereinafter described, from which as will be evident the screw 4 and hence the casing 3 is insulated from said support.

Between the upper or removable portion 75 of the casing 3 and the insulating body 2, the insulation 10 may be disposed, the upper marginal portion of said insulation 10 overlying the inner externally shouldered end of the bushing 12 inclosed by the central 80 neck 13 of said upper portion of the casing. Through this insulating bushing the wires 14 extend and are connected as by screws 15 with the bodies of the wire connecting and contact members 16. Said bodies fit 85 flatwise against the top of the insulating body 2 and are held in place in some convenient manner as by screws 17 extending through the insulating body from below and the threaded upper ends of which fit threaded openings in the bodies of the respective wire connecting and contact members 16. These wire connecting and contact members 16 as illustrated have resilient U-shaped contact portions 18 which depend or extend 90 into the chamber 8, being diametrically opposite each other and being adapted to be engaged by a switching member such as 20 when the latter is on. The switching member 20 is mounted for oscillation or swinging movement and comprises companion side branches connected by the pin 21 of metal, constituting a suitable bridging element.

I will now describe a suitable support for the switching member 20, which support 105 can be made from metal formed up in some suitable manner. This support is preferably made in one piece, and comprises two sides 22 connected by the cross piece 23, said sides or cheeks 22 having lips 24 at their 110 ends bent toward each other, transversely aligned and slightly separated. This forms

- a casing or box-like support or receiver. The yoke-like switching member 20 straddles the sides 22 and is pivoted thereto at 25, the center of motion of the switching member being located practically centrally or midway of the sides or cheeks 22. The sides or cheeks 22 have near their ends on their upper edges and in proximity to the lips 24 the outturned lugs 26 constituting 10 suitable stops, for arresting the switching member 20 when in the on and the off positions thereof. The sides 22 are provided with outwardly disposed feet 27 resting on the bottom of the cavity 8 and connected 15 therewith in any suitable manner as by the screws 28.
- Supported for oscillation by the pivot or pin 25 is a gear member or pinion 29. From this it will be understood that the gear member 20 or pinion and switching member 20 are coaxial, although they are capable of relative movement for a reason that will herein-after appear. This gear member 29 as will be also evident, is situated between the sides 25 or cheeks 22 and it co-operates with suitable actuating members as 30 and 31. Each actuating member has a body as 32 generally consisting of a flat metal strip mounted for back and forth movement between and thus 30 guided by the sides 22 aided by the end lips 24, the latter maintaining the rack members 32 in mesh with the two sets of teeth 33 and 34 of the gear member 29. The heads or manipulating portions of the actuating members 30 and 31 as represented, consist of insulating buttons molded upon and suitably anchored to the rack members 32. The insulating body 2 has holes 35 opening into the chamber 8 to receive and guide 35 the two button or manipulating portions of the actuating members 30 and 31, the casing 3 having suitably positioned perforations as 36 also intended for the passage of said buttons. The gear member or pinion 29, 40 constituting a convenient motion transferring device, has as shown a peripheral notch into which is driven the pin 37, the pin being located approximately centrally between the two sets of teeth 33 and 34. The 45 outer ends of this pin project through transversely-alined slots 38 formed in the sides 22. Both said slots 38 are arcuate, their arcs being struck from the center of motion of the gear member 29.
- 50 Connected with the projecting portions of the pin 37 are coiled springs 39, the upper ends of the springs being connected with the pin 21 from which as will be inferred the gear connected ends of the springs are 55 normally at one side of a dead center line intersecting the center of connection between the springs 39 and the switching member 20 and the center of motion of the gear member 29 and also in the present case the 60 center of motion of the switching member 65
20. By moving the gear connected ends of the springs across this dead center line, the springs will act to snap the switching member from one of its two positions to the other, and when the gear connected ends of the 70 springs are again moved across said dead center line, the operation in question will be reversed, by reason of which the switching member can be moved between its on and off positions with an accelerated or snap movement. 75
- In Figs. 2 and 6 the switching member is in the off position, the actuating member 30 being down and the actuating member 31 being up. By thrusting upward on the actuating member 30 the rack teeth of the body or rack portion 32 thereof will rock the gear 29 in the direction of the arrow in Fig. 7, thus swinging the pin 37 toward and then across the dead center line to effect a 85 corresponding function with respect to the outer ends of the two springs 39 and at the same time through the teeth 34 to lower the actuating member 31. When the outer ends of the springs cross the dead center line the 90 switching member 20 is instantly moved from off to on position. With the actuator 31 down and the actuator 30 up, the switching member can be moved to off by thrusting upward on the actuating member 31. 95
- The rack or body portions of the actuating members 30 and 31 are provided at opposite ends of their teeth each with a pair of curved stop faces 32', which alternately engage the plain portions of the periphery of the gear member 29 to limit the longitudinal or endwise movement of the two actuating members. That is to say this provides a simple construction for arresting said actuating members when the switching member 100 is in the on and the off positions.
- What I claim is:
1. An electric switch comprising a support, a yoke like switching member straddling and pivotally connected with said support, a motion transferring member carried by the support and provided with laterally extending portions, springs connected with said laterally extending portions and with the switching member, those ends of the 110 springs which are connected with the laterally extending portions being normally at one side of a dead center line intersecting the center of motion of said motion transferring member and the center of connection between the springs and the switching member, said motion transferring member being oscillatory to move those ends of the springs which are connected with said laterally extended portions alternately across said dead center line and thereby cause on and off movements of the switching member, and independent actuating members for rocking said motion transferring member. 115
  2. An electric switch comprising a sup- 120

- port, a rocking gear carried by the support, actuating members also carried by said support, having racks to mesh with the teeth of the gear member and adapted to rock said gear member alternately in opposite directions, a swinging switching member mounted on said support, and spring means connected with the switching member and with the gear, that end of the spring means which is connected with the gear being normally at one side of a dead center line intersecting the center of motion of said gear and the center of connection between the spring means and the switching member.
15. An electric switch comprising a switching member, a motion transferring gear movable about the same axis as the switching member, spring means connected with the motion transferring gear and with the switching member, the motion transferring gear connected end of the spring means being normally at one side of a dead center line intersecting the center of motion of the motion transferring gear and the switching member and the center of connection between the spring means and the switching member, said motion transferring gear being oscillatory to move that end of the spring means which is connected therewith alternately across said dead center line, and independent actuating gear members in mesh with and for rocking said motion transferring member.
4. An electric switch comprising a support, a rocking gear inclosed by the support, actuating members having racks, diametrically placed with respect to the gear and the teeth of which mesh with the teeth of the gear to rock said gear alternately in opposite directions, the racks being inclosed and guided by the support, a switching member straddling and pivotally connected with the support, and spring means connected with the gear and with the switching member, the gear connected end of the spring means being normally at one side of a dead center line intersecting the center of motion of the gear and the center of connection between the spring means and the switching member.
50. 5. An electric switch comprising a support, a rocking gear inclosed by the support, actuating members having racks, diametrically placed with respect to the gear and the teeth of which mesh with the teeth of the gear to rock said gear alternately in opposite directions, the racks being inclosed and guided by the support, a switching member straddling and pivotally connected with the support, and spring means connected with the gear and with the switching member, the gear connected end of the spring means being normally at one side of a dead center line intersecting the center of motion of the gear and the center of connection between the spring means and the switching member.
55. 6. An electric switch comprising a support, a rocking gear inclosed by the support, actuating members having racks, diametrically placed with respect to the gear and the teeth of which mesh with the teeth of the gear to rock said gear alternately in opposite directions, the racks being inclosed and guided by the support, a switching member straddling and pivotally connected with the support, and spring means connected with the gear and with the switching member, the gear connected end of the spring means being normally at one side of a dead center line intersecting the center of motion of the gear and the center of connection between the spring means and the switching member.
60. 7. An electric switch comprising an insulating body having a chamber, a yoke-like support fixed within said chamber, a gear member pivotally mounted between the sides of the support, a yoke-like switching member straddling the support and mounted for swinging movement, springs connected with the switching member, the gear member having lateral extensions to which the springs are connected, and racks in mesh with the gear member for alternately oppositely oscillating the same, the racks having buttons extending to points outside the insulating body.
7. An electric switch comprising an insulating body having a chamber, a yoke-like support fixed within said chamber, a gear member pivotally mounted between the sides of the support, a yoke-like switching member straddling the support and mounted for swinging movement, springs connected with the switching member, the gear member having lateral extensions to which the springs are connected, and racks in mesh with the gear member for alternately oppositely oscillating the same, the racks having buttons extending to points outside the insulating body, said support having inturned lips overlying the racks to guide the same.
8. An electric switch comprising an insulating body having a chamber, a yoke-like support fixed within said chamber, a gear member pivotally mounted between the sides of the support, a yoke-like switching member straddling the support and mounted for swinging movement, springs connected with the switching member, the gear member having lateral extensions to which the springs are connected, and racks in mesh with the gear member for alternately oppositely oscillating the same, the racks having buttons extending to points outside the insulating body, said support having inturned lips overlying the racks to guide the same and also having outturned lugs to arrest the motion of the switching member when in the on and the off positions thereof.
- In testimony whereof I affix my signature in presence of two witnesses.
- JOSEPH SACHS.
